UNITED STATES PATENT OFFICE.

MAX DRUCKERMAN, OF BROOKLYN, NEW YORK

SEWING-MACHINE.

1,108,347.

Specification of Letters Patent.

Patented Aug. 25, 1914.

Application filed June 25, 1913. Serial No. 775,669.

To all whom it may concern:

Be it known that I, MAX DRUCKERMAN, a citizen of the United States, and a resident of Brooklyn, in the county of Kings and State of New York, have invented certain new and useful Improvements in Sewing-Machines, of which the following is a specification, taken in connection with the accompanying drawings, which form a part 10 of the same.

My invention relates to sewing machines and more particularly to an embroidery sewing machine having a vertically and laterally movable needle and one adapted to make extremely long stitches, as well as short ones, and any intermediate length of stitches between the maximum and minimum.

I am aware that there are sewing machines having a vertically and laterally movable needle making a zigzag stitch and I make no claim broadly to such a machine. There are certain structural limitations to such machines which prevent them making 25 an excessively long stitch. I have obtained the most beautiful effects in embroidery by greatly lengthening the stitch, over any length of stitch which can be made by any of the old forms of sewing machines having 30 a vertically and laterally movable needle. For example the maximum length of stitch for the ordinary old form of zigzag sewing machine is about seven-sixteenths of an inch, the stitch can then be graduated down 35 to the minimum, by varying the lateral throw of the needle bar in the manner well-known in this art. By my invention I increase the maximum length of the stitch to any desired length depending upon the 40 size of the relative parts of the machine. With the operating parts of the machine substantially the same size as that of the ordinary zigzag machine making the maximum length of stitch of say about seven-six- 45 teenths of an inch I can make, by my invention, a stitch an inch or one and a quarter inches long, and vary the length of the intermediate stitches in any suitable manner so as to produce beautiful embroidery 50 effects. This difference in the length of the maximum stitches permits my embroidery machine to embroider designs and produce effects which are wholly novel and which can not be made by the ordinary zigzag sew-

ing machine having a comparatively short maximum stitch.

My invention further relates to a novel take-up mechanism which is preferably used with the other parts of my sewing machine so as to play out long portions of 60 thread for my machine, though the take up mechanism might be used with some other form of sewing machine.

My invention further relates to a certain combination of an accelerator used in connection with a rotary shuttle so as to accelerate the movement of the shuttle at a certain point in its rotation.

It further relates to certain details of construction and combination of elements which 70 will be more fully hereinafter described in the specification and pointed out in the claims.

In the accompanying drawings showing one illustrative embodiment of my invention 75 and in which the same reference numerals refer to similar parts in the several figures, Figure 1 is a side elevation of my improved sewing machine; Fig. 2 is an end elevation of the head and shuttle mechanism; Fig. 3 80 is an inverted plan view of the sewing machine bed; Fig. 4 is a detail vertical section through a portion of the sewing machine bed and showing the shuttle, needle and accelerator in side elevation; Fig. 5 is a 85 transverse vertical section substantially on the line 5—5 of Fig. 4 looking in the direction of the arrows; Fig. 6 is a fragmentary plan view of the sewing machine head showing the take-up mechanism; Fig. 7 is an end 90 elevation of the head showing the take-up mechanism; Fig. 8 is a fragmentary transverse vertical section substantially on the line 8—8 of Fig. 1; Fig. 9 is a fragmentary side elevation of the head and shuttle showing 95 the needle beginning to make a stitch; Fig. 10 is a view similar to Fig. 9 showing the parts at the next step in the making of the stitch; Fig. 11 is a view similar to Figs. 9 and 10 showing the next step wherein the 100 hook of the shuttle has caught the needle thread and begins to form the loop; Fig. 12 is a view similar to Fig. 11 showing the hook with the shuttle at substantially a quarter revolution from that shown in Fig. 11 and 105 with the take-up mechanism in the position at that part of the stitch. Figs. 9, 10, 11 and 12 show substantially one complete cycle.

of the parts in the formation of a stitch; Fig. 13 is a diagrammatic plan view of a fabric embellished with the excessively long stitches, as well as some short stitches, made by my improved embroidery sewing machine; Fig. 14 is a fragmentary plan view of the fabric such as is Fig. 13 showing one of the many forms of embroidery which may be made with the excessively long 10 stitches contrasted or used in connection with the short stitches to obtain the most beautiful effects in embroidery; and Fig. 15 is an inverted plan view of the fabric showing the coöperation of needle thread loops 15 and the substantially straight shuttle thread.

In the illustrative embodiments of my invention shown in the drawings, 1 is a sewing machine having a head 2, a bed 3, a rocking arm 4 provided with a slot 5, in which slides 20 the slide 6 to which is connected a pitman 7, the other end of which is connected with a sleeve 8 within which reciprocates the needle bar 9 carrying the needle 10.

The presser foot bar 11 carries the ordinary presser feet 12, 12 coöperating with the ordinary feed dogs 13, 13, Fig. 4. The presser foot bar is controlled by the ordinary release lever 14, Fig. 2, coöperating with the arm 15 to lift the presser feet to release the goods. The sewing machine head is also preferably provided with an ordinary tension release lever 16 pivoted at 17 and operated by the screw or pin 18 operating in the slot 19, and, when the presser foot lever 35 14 is raised, it serves to throw the end 20 of the lever 16 into contact with the ordinary spring tension member 21 and release the tension upon the needle threads 22 in an old and well understood manner.

40 The head is provided with the ordinary needle bar shaft 23, Fig. 1, having cranks 24, 24 with which coöperate pitmen 25, 25 connecting the main or needle bar shaft 23 to the main shuttle shaft 26 so that the rotation of the needle bar shaft 23, by applying any suitable power to that shaft, as for example to the pulley 27, will cause the needle bar shaft and the main portion of the shuttle shaft 26 to operate in unison.

50 The needle bar shaft 23 is provided with the ordinary cam (not shown) to operate the rock arm 4 in the usual and well known manner in this class of machines. On the end of the needle bar shaft 23 I provide a head 28 (Figs. 1 and 8) having a cam slot 29 to coöperate with the main take up 30, and preferably the same cam slot coöperates with the auxiliary take up 31 which is pivoted on the head of the sewing machine at 32 and extends out adjacent to the main take up 30. I connect a pitman 33 to the head 28 in any suitable manner, such as by the pin 34, the other end of the pitman being connected to the collar 35 fast to the 65 needle bar 9. On the head of the machine I

70 pivot a sleeve 36 on the arm 37 by means of the pin 38 so that the sleeve 36, and particularly the needle bar 9 with its needle 10, will swing in the same vertical plane in which the shuttle 39 rotates for a purpose which will be more fully hereinafter pointed out in detail. Below the bed 3 is mounted in suitable brackets the shuttle shaft 26, previously noted, which however does not extend to the shuttle, being broken 75 at some intermediate point as for example at 40, Fig. 3. Upon the shaft 26 I mount a gear 41 and upon a countershaft 42 I mount a similar gear 43, the relation of the gears being one to one. Upon the intermediate shuttle shaft 44 I mount the gear wheel 45 having it mesh with a larger gear wheel 46 upon the countershaft 42. The relation of the gear wheels 45 and 46 is preferably two to one, the shaft 44 being revolved twice to the one revolution of the countershaft 42. Upon the end of the intermediate shuttle shaft 44 I mount an accelerator 49 which at a certain predetermined point of the revolution of the shuttle 90 39, will accelerate its movement so that the loop made by the needle thread 22 will be quickly thrown past the center 95, Fig. 11 of the shuttle to insure the loop never catching on the shuttle at a point directly beneath its axis of rotation 47; for if this should occur the upward pull on the needle thread would tighten the loop 48 and cause the needle thread to break.

95 The accelerator 49 Figs. 3 and 4, consists preferably of a disk 50 mounted upon the intermediate shuttle shaft 44 to which is pivoted a link 51 by means of a pin 52. The other end 55 of this link 51 is pivoted to an arm 53 carried by the accelerator shaft 54. The end 55 of the link 51 will be caused, in an obvious manner, to move to and from the axis of the rotation of the shuttle shaft 44 so that during that period of rotation of the shuttle shaft 44 and the end 55 of the link 51 when they are nearest the periphery of the disk 50, the shaft 54 will be caused momentarily to move with greater speed than its normal rotation. The parts are so arranged that this increased speed of rotation of the shaft 54 occurs just as the needle loop 48 is about to reach a point 95 Fig. 11 directly beneath the axis of rotation 47 of the shuttle 39 so that the rotary movement of the shuttle 39 will be accelerated or speeded up momentarily until the loop 48 passes this critical point in its formation. This acceleration therefore occurs once on each revolution of the shuttle. The accelerator shaft 54 drives the shuttle 39 in any suitable manner preferably by means of the gear 57, idler 58 and the gear 59 mounted upon the shaft 60. The fork 61 and the cam 62 operating it are in themselves old and coöp- 115 120 125 130

erate with the ordinary form of stitch controller shaft 63. The cam 64 upon the shaft 26 and the fork 65 mounted upon the rock shaft 66 are of the ordinary construction to operate the feed dogs 13, 13. In my machine they operate the feed dogs once to two revolutions of the shuttle.

One portion of my invention, as previously noted, is to greatly increase the length of the stitch over and above that which can be made by any zig zag sewing machine prior to my invention. A common expedient in the ordinary form of zig zag sewing machine is to pivot a link or similar member on a vertical pivot on the head of the machine so that it would act as a guide or sleeve for the needle bar 9, the needle bar being caused to move vertically and also laterally but in the arc of a circle, the center of which would be the pivot connecting the link with the head. This is the ordinary form well known in the trade. In such a machine the needle bar and the needle travel in the arc of a horizontal circle while the hook 67 of the shuttle 39 rotates vertically at a tangent to that arc. It is, therefore, obvious that only in a certain portion of that arc so formed will the hook 67 of the shuttle 39 catch the needle loop 48 formed by the needle thread 22. It is, therefore, impossible to make a comparatively long stitch with such a machine in which the needle bar, equivalent to the bar 9, moves in the arc of a circle while the hook 67 moves at a tangent to that arc, for the reason that the hook would not catch the loops formed by the needle at the ends of the arc for the reason that in that position the loop would be out of the path of the rotating hook 67.

By my invention I mount the needle bar 9 in any suitable manner, to swing in the same vertical plane in which rotates the shuttle 39. As previously explained I accomplish this result by mounting the sleeve or guide 36 so that it will swing in a vertical plane over the rotating shuttle 39 and will permit the oscillation of the needle bar 9 in the same vertical plane that the shuttle 39 rotates in. I am therefore enabled to greatly increase the length of the stitch formed by the machine for the loop, wherever formed, will always be in the path of the hook 67 of the shuttle 39. With the parts of the machine the same size as in the old form in which the needle bar travels in the arc of a circle at a tangent to the shuttle, I can increase the length of the stitch from about seven-sixteenths, which is the length of the old stitch, to about one inch or 14 inches. Of course, by enlarging the different parts of the shuttle mechanism and needle bar operating mechanism the length of the stitch can be proportionately increased. I have obtained excellent results in making

embroidery by making the length of the maximum stitches about one inch long. The lateral throw of the needle bar 9 may be regulated by the controller rod 68, the lever 69, link 70, lever 71, rock shaft 72 and lever 73 connected to the link 74 by operating the controller rod 68 in any suitable manner either automatically such as shown in my companion application Serial No. 736,180, filed December 11, 1912, or by any ordinary knee lever (not shown).

Omitting for the moment my improved take up device which is used to feed a large amount of thread to form the successively long stitches, and to permit instant change from a long to a short stitch or vice versa without affecting the successful feeding of the thread, the operation is as follows: Power being applied in any suitable manner to the pulley 27, preferably from some source of electric or other source of power, the needle bar shaft 23 is rotated which causes the vertical reciprocation of the needle bar 9 by the link 33 being connected to the head 28 and secured to the needle bar by the collar 35, the needle bar reciprocating vertically freely through the sleeves 36 and 8. In addition to this vertical reciprocation the needle bar 9 is caused to move in a straight line substantially at right angles to the horizontal axis of the shuttle 39 by the pitman 7 and rocking arm 4, which is old in the art and its operation need not be here described in detail except to state that the rocking arm 4 and its operating parts, in themselves, are no portion of my invention, though a portion of my invention comprises the combination of such rocking arm with other parts of the mechanism. At the same time that the needle bar shaft 23 is rotated, the shuttle shaft 26 is operated by the pitmen 25, 25 which through the mechanism previously described, transmits power to the countershaft 42 (Fig. 3) causing it to revolve at the same speed as the shaft 42. The gear wheels 46 and 45 will cause the shuttle 39 to rotate twice as fast as the rotation of the needle bar shaft 23 and the shaft 26. By this I am enabled to permit a plurality of rotations of the shuttle 39 to one coöperating movement of the needle 10. Preferably this relation is as I have shown in the drawings, which permits two rotations of the shuttle to one coöperating movement of the needle bar 9. I have found in practice that to permit the needle to lay down the thread for my excessively long stitches that it is preferable to permit the shuttle 39 with the hook 67 to rotate idly, without catching a loop 48, every other rotation. This gives the needle time to form one loop 48 at one end of its travel and the next loop 48 at the other extreme end of its travel, the hook 67 between these two extreme movements of the needle, 130

rotating once idly but every other time catching the loop 48 once at the end 75 of the slot 76 in the plate 77, Fig. 11, and, on the second revolution of the shuttle 39 from 5 the position shown in Fig. 11 catching the loop 48 when the needle bar 9 and needle 10 have been reciprocated by the rocking arm 4 and connections from the extreme end 75 of the slot 76 to the other extreme end 10 78 of the same slot. Fig. 11 shows the loop being caught by the hook at one extreme movement of the needle bar 9, it being readily seen that when the needle bar is depressed and forced into the other extreme end 15 78 of the slot 76, that the hook 67 will then also catch the loop, for the vertical and lateral reciprocation of the needle bar 9 and needle 10 is in the same vertical plane in which rotates the shuttle 37.

20 In Fig. 9 the hook 67 of the shuttle is rotating idly without coöperating with a loop. In Fig. 10 the needle is about to enter the cloth which it does in Fig. 11 forming the loop 48 which is then immediately 25 caught by the hook 67 and carried around in the ordinary way until the loop is about to pass the point 95 when the accelerator mechanism, previously described, as well as a portion of the take up mechanism to be 30 later described, will cause the loop to be quickly pulled past this point and clear the hook. The loops 48 so formed coöperate in the ordinary manner with the shuttle or locking thread 56. It will be noted in Figs. 35 9 to 12 and more particularly in Fig. 15 that while my exceedingly long stitches 79 as well as the loops 80, appearing on the reverse of the fabric 81, take a great length of the needle thread 22 no greater length of 40 shuttle thread 56 is required than on the old form of zig zag embroidery machines, or for that matter as much, for the reason that in my machine I preferably so arrange the parts that the shuttle or locking thread 56 45 extends substantially in a straight line which not only improves the looks of the reverse of the embroidered fabric 81, but also takes a shorter length of shuttle thread 56 thus saving the time of continually re- 50 placing the bobbin or thread holder 82 either with a new bobbin or stopping to fill the old one.

Another portion of my invention is my improved take up mechanism used alone or 55 in combination with the other elements of my embroidery sewing machine, which will feed the relatively large quantity of thread to the needle to make the stitches of maximum length without putting appreciable 60 tension upon the thread, which has been worked into the fabric 81 which would pucker the goods, or in any manner marring the appearance of the embroidery. And further, such a take up mechanism as will 65 automatically adjust itself to feed the thread

for the longest stitches as well as for the shortest stitches, or any intermediate length stitches.

I have shown by way of example one embodiment of my take up mechanism, though 70 my invention is not to be limited to this particular form, but on the contrary is limited only by the terms of my claims. This take up mechanism is shown more in detail in Figs. 2, 6, 7, and 9 to 12 inclusive. The 75 needle thread 22 passes through an ordinary guide 83, tension devices 84, 21 and 85, then through the loop 86 of the coil spring take up 87 mounted on the pin 88, thence through the ordinary take up 30 thence under the rigid guide 90, thence through the auxiliary take up 31 and thence to the needle 10 preferably passing through any form of old rigid guide 92. Upon the auxiliary take up 31 I mount an arm 89 coöperating 85 with a slot 91 in the plate 93 pivotally mounted upon the pin 88. This plate 93 is provided with an arm 94 to coöperate with the loop 86 of the spring take up 87. When the position of the parts are as shown in Fig. 9 90 the shuttle 39 is about to make one revolution without having its hook coöperate with the needle thread. In this position, the auxiliary take up 31 has been raised to complete the stitch and draw the loop 48 taut 95 on the reverse of the fabric 81 and at the same time raise the plate 91 so that its arm 94 will free the spring take up loop 86 permitting it to exert a spring action upon the needle thread 22 to assist in throwing the 100 loop past the center 95, Fig. 11, of the shuttle 39. In this Fig. 9 the needle is about to make another of its maximum stitches, the needle thread 22 having been previously 105 played out by the take-up mechanism. In this position the auxiliary take up 31 is at its extreme raised position while the main take up 30 is in its extreme lower position. On the next movement of the parts the main take up 30 moves vertically at relatively 110 high speed taking with it the needle thread 22 which, however, is caught by the fixed guide 90, this guide lying between the main take up 30 and the auxiliary take up 31. As this main take up passes the fixed guide 115 90 it pulls the needle thread 22 from the spool and through the tension devices 84, 21 and 85 with considerable speed so as to have sufficient thread for the next stitch. My maximum stitches are so great that it 120 is necessary to prevent the main take up 30 exerting any strain or pressure upon that portion of the needle thread which is worked into the embroidered article 81. If this were not done the goods 81, as previously noted, would become puckered and ruined or the needle thread would be continually breaking. I, therefore, "pacify" 125 the needle thread by arranging the auxiliary take up 31 so that it will descend 130

slowly while the main take up 30 is ascending quickly. This permits the main take up 30 to pull quickly upon the needle thread passing through it so as to quickly obtain sufficient thread for the next stitch and at the same time the fabric 81 is protected from being puckered, or the needle thread being broken by the needle, upon the upward pull of the main take up 30, by having the auxiliary take up 31 relieve the strain upon the needle thread which is about to be passed through the needle. By this arrangement the quick upward movement of the main take up 30 feeds out sufficient thread for the next stitch, the slight pull backward of the needle thread through the auxiliary take up being inappreciable and not being communicated to the goods. The needle thread 22 is then played out sufficiently for the next stitch, Fig. 10, and the main take up 30 will then begin to descend leaving the needle thread 22 slack as shown in Fig. 11. The needle then enters the fabric 81 and forms the next loop 48, the shuttle 39 enlarging that loop as shown in Fig. 12. While the shuttle is operating to enlarge the loop 48 the main take up 30 descends toward the presser feet so as to remove all tension from the needle thread 22 for such tension would prevent the shuttle successfully making an enlarged loop 48. At the same time the auxiliary take up or "pacifier" 31 descends carrying with it the plate 93 with its arm 94 which bears on the loop 86 of the spring take up 87 and prevents the spring take up exerting any tension upon the needle thread 22 during the initial stage of making the loop. The needle then rises, while the shuttle 39 proceeds to enlarge the loop 48, the parts being then substantially in the position shown in Fig. 12. When the loop 48 just passes the point 95, Fig. 11, directly beneath the longitudinal axis of the shuttle 39, the auxiliary take up 31 begins to rise which immediately releases the pressure of the arm 94 upon the loop 86 of the spring take-up 87 so that this spring take up will instantly exert a pull upon the loop 48 just as it is about to pass the point 95 and will pull the loop free of the hook 67, so that it will coöperate with the shuttle thread 56 and form the thread loops 80 on the reverse of the fabric 81, the loops being given a complete and final pull by the auxiliary take up 31. The parts then have made one complete cycle and are in position to have the main take up pull sufficient thread from the spool for the next stitch, and so on in the manner previously described at length.

In the operation of the take up mechanism so far described I have assumed that each stitch is of the maximum length which can be made by the machine. In embroidery, for which this machine is particularly adapted,

it is necessary to frequently change the length of stitch to obtain the most beautiful effects, either by contrasting the maximum length of stitches 79 with the minimum length of stitches 97 or by gradually tapering the stitches from the maximum to the minimum to obtain the desired result. This requires that the take up mechanism can adjust itself instantly and automatically to the particular length of stitch which may for the moment be used. If after making one or more stitches of maximum length it is desired to make a shorter stitch by operating the rock arm 4 in the manner previously described, it is obvious that on the first short stitch, jumping from the maximum stitch, there will be a surplus of needle thread which has been previously played out by the main take up 30. This surplus is taken up by the spring take up 87. The spring take up 87, however, immediately permits the maximum stitch to be made automatically by again moving the rock arm 4, the take up mechanism automatically adjusting itself to the particular length of stitch which may at the moment be made by the machine.

Having thus described this invention in connection with the illustrative embodiments thereof to the details of which I do not desire to be limited, what is claimed as new and what it is desired to secure by Letters Patent is set forth in the appended claims.

1. The combination in a sewing machine of a vertically and laterally movable needle, means to operate it both vertically and laterally in a single vertical plane, a rotary shuttle, a pivoted main take up, a spring take up, and an independently pivoted auxiliary take up.

2. The combination in a sewing machine of a vertically and laterally movable needle, means to operate it both vertically and laterally in a single vertical plane, a rotary shuttle, a main take up, a spring take up, an auxiliary take up, and means to render the spring take up inoperative during the initial stages of the formation of the loop.

3. The combination in a sewing machine of a vertically and laterally movable needle, means to operate it both vertically and laterally in a single vertical plane, a rotary shuttle, take up mechanism having means to play out a long length of thread for the maximum length of stitches, and resilient means to automatically take up the surplus length of thread when the sewing machine makes a shorter length of stitch than its maximum, and means to render the resilient means inoperative during a portion of the formation of the stitch.

4. The combination in a sewing machine of a vertically and laterally movable needle, means to operate it both vertically and laterally in a single vertical plane, a rotary

shuttle, a pin upon the head of the machine, a coil spring mounted on the pin and provided with a loop to receive the thread, a main take up, an auxiliary take up, a fixed 5 guide, a plate mounted on the pin and provided with an arm to coöperate with the loop of the coil spring, and means carried by the auxiliary take up adapted to actuate the plate mounted on the pin.

10 5. The combination in a sewing machine of a rotary shuttle mounted to rotate in a vertical plane, a needle bar provided with means to permit it to swing in the same vertical plane that the shuttle rotates in, means 15 to reciprocate the needle bar vertically, a rocking arm, a slide mounted on the rock-

ing arm, a pitman connecting the slide with the needle bar, and means to operate the slide.

6. The combination in a sewing machine 20 of a vertically and laterally movable needle, means to operate it both vertically and laterally in a single vertical plane, a rotary shuttle, a main take up pivoted on the head of the sewing machine, a spring take up, 25 and an auxiliary take up independently pivoted on the head of the machine.

MAX DRUCKERMAN.
